UNITED STATES PATENT OFFICE

95,278

DESIGN FOR A TEAPOT

Edna Clark Mills, Des Moines, Iowa

Application July 27, 1934, Serial No. 52,713

Term of patent 3½ years

To all whom it may concern:

Be it known that I, Edna Clark Mills, a citizen of the United States, and a resident of Des Moines, in the county of Polk and State of Iowa, have invented a certain new, original, and ornamental Design for a Teapot, of which the following is a specification, reference being had to the accompanying drawing, forming part hereof, in which

Figure 1 is a top plan view of the teapot, showing my design.

Figure 2 is a front elevational view.

Figure 3 is a side elevational view.

Figure 4 is a rear elevational view.

I claim:

The ornamental design for a teapot as shown.
Des Moines, Iowa, November 4, 1933.

EDNA CLARK MILLS.
